UNITED STATES PATENT OFFICE.

HENRY B. MORRIS, OF GENEVA, NEW YORK, ASSIGNOR, BY DIRECT AND MESNE ASSIGNMENTS, TO THE MORRIS WEAVING COMPANY, OF SAME PLACE.

LOOM.

SPECIFICATION forming part of Letters Patent No. 427,104, dated May 6, 1890.

Application filed June 1, 1888. Serial No. 275,764. (No model.)

To all whom it may concern:

Be it known that I, HENRY B. MORRIS, a citizen of the United States, formerly residing at Hornellsville, in the county of Steuben and State of New York, but now a resident of Geneva, in the county of Ontario and State aforesaid, have invented certain new and useful Improvements in Looms for Weaving Textile Fabrics, of which the following is a full specification.

My present invention relates chiefly to that class of looms for weaving fabrics composed of bulky or rigid material—such, for instance, as split cane, rattan-pith, wooden strips, wire, or like substances—in which each warp-thread is carried on a separate reel capable of independent movement athwart the line of warp to open a shed, and a weaving-arm, weft-guide, or weft-carrier traversed intermittently in alternately-opposite directions across the warp-threads in the shed thus opened to lay the weft therein.

The objects of my invention are to impart a wide range of movement to the warp-reels, to enable them at the proper time to clear the intersecting path of the weft-carrier, to determine which reels shall be actuated to open the shed, to properly guide the warp-threads both vertically and laterally, so to control the feed that it may automatically be stopped or started whenever desired without interference with the weaving, and, finally, to do all this by simple and effective mechanism, which ends I attain by novel constructions and organizations of instrumentalities hereinafter specifically designated.

The accompanying drawings represent so much of a loom adapted for weaving "split cane"—embracing all the improvements herein claimed—as is necessary to illustrate the subject-matter thereof. The cloth-beam end of the loom I call the "front," the weft-carrier end the "rear." That side of the loom on the right of one facing the loom at the weft-carrier end I term the "right" side, the opposite one the "left."

Figure I represents an elevation of the right side of the loom with portions of the standards 2 and 18 removed, the weft-guide plate 56 being shown in section the better to ex-

hibit the working parts. Fig. II is a plan with a portion of the pattern-belt 34 removed. Fig. III is a plan, partly in section, upon the broken line D, Fig. I, substantially above the normal warp-line. Figs. IV to IX, both inclusive, are detail views, some of them on the same scale as Fig. I. Figs. IV, VI, and IX are on a larger scale. Fig. IV is a side elevation of one of the warp-carriers and its guides; Fig. V, a rear elevation of a part of the series of warp-carriers and guides. Fig. VI represents vertical and horizontal longitudinal sections through the point of my improved weaving-arm or weft-carrier. Figs. VII and VIII are respectively side and front elevations of the pattern-chain and feeler-rods and mechanism for operating them. Fig. IX is a side elevation of the feed-rolls.

The mechanism is shown as mounted in a suitable main frame 0, consisting, essentially, of longitudinal side pieces and transverse connecting end pieces.

The various working parts of the loom are actuated by a driving-shaft 1, journaled in this frame and projecting beyond it at each end to carry the necessary gearing and pulleys to drive it from any suitable prime mover and in turn to drive other parts of the loom. Standards 2 near the rear end of the frame support transverse bars 3 on opposite sides of and parallel with the median or normal plane of the warp. A row of guides 5 6 projects inwardly from each of these bars, preferably in the form of straight pins polygonal in cross-section, arranged with the corresponding pins in the same line or end to end transversely to the warp, and on each side thereof, so as to leave a passage for the weft-carrier, hereinafter described. Warp-carriers, preferably consisting of oblong blocks 7, each centrally and longitudinally perforated with an opening corresponding in outline with that of the cross-section of the guides 5 6 and of a length greater than the space between the inner ends of the guides, move freely endwise thereon, one on each pair, each independently of the others, and all normally remain on the same side of the warp. A lever 8 is pivoted near one end to one side of each warp-carrier at an intermediate point, so as

- to allow it to swing around its pivot in a plane parallel with the side of the carrier. The free end of each lever carries a warp-reel 9, capable of turning freely on its central pivot, 5 each reel carrying a single warp-thread, which is led from the reel through a horizontal slot in its respective warp-carrier, and thence through the loom to the warp-beam, as usual. Suitable tension on each warp-thread is maintained by a flat spring 13, secured by an adjusting-screw 14 to the carrier and pressing on the end of a tension-pin 15, movable endwise in a recess in the carrier athwart the warp-slot 11. (See Fig. IV.)
- 15 The drawings show the warps as fed from the lower side of the reels and the tension device on the bottom of the carrier, the transverse bar 4 being recessed to receive the springs with the warp-carriers in their normal 20 position.
- 25 When split cane composes the warp, the threads are made continuous by gluing together or otherwise joining the ends of the short pieces of which this material commonly consists, the glazed side of the cane preferably coming uppermost. The slots are made oblong in cross-section, with their longer sides parallel with the warp and so close together as to prevent the flat strips of cane from 30 turning.
- 35 In nearly all woven fabrics the warp-threads lie so close together that it would be difficult to make the separate warp-carriers narrow enough to arrange them as compactly as the warp-threads. This difficulty I obviate by placing them farther apart, which of course causes them to occupy a much wider space laterally than the width of the fabric; but this dispersion I compensate for by converging 40 the warp-threads to their proper position near the point of insertion of the weft, which I term the "weaving-line," which is close to the feed-rolls and shown by the dotted line C, Fig. III. This convergence is effected by a 45 comb, hereinafter described. In order to accommodate this divergence of the warp-threads, the sides of the warp-carriers 7 are correspondingly inclined on each side of the vertical central line of the warp, and their guide-slots 11 are also correspondingly inclined. As 50 the reel-arms 8 move parallel with these inclined faces of the carriers, they diverge correspondingly, thus leaving ample room between the reels 9. (See Fig. III.)
- 55 The warp-reels are traversed athwart the median line of the warp to open the shed as follows: A rock-shaft 17 extends across the loom over and parallel with the weaving-line C, above, in advance of, and parallel with the 60 line of warp-carriers 7, being journaled in the main standards 18 and projecting at each end beyond the frame. Radius-bars 19, rigidly connected with these projecting ends, extend to a point in line with the warp-carriers and are united by a cross-shaft 20. One 65 of the radius-bars 19 extends beyond its pivot in the opposite direction and is pivoted to a

link-rod 21, the other end of which traverses a suitable guide 22 on the main frame and carries a friction-roller 23, engaging the 70 grooved cam 24 on the driving-shaft 1, thus imparting a periodical oscillating motion to the shaft 20 transverse to the line of the warp. A series of trip-levers 25, one for each warp-carrier, rock centrally and independently on the 75 shaft 20 parallel with the warp-threads and each in line with its respective carrier, with which it can engage when in proper relation by a pin 26 on the free end of the lever entering a recess in the carrier. (See Fig. I.) 80 The opposite ends of these trip-levers are flexibly connected by parallel rods 27 with one arm of one of a corresponding set of bell-crank levers centrally and loosely pivoted on the rock-shaft 17. As the bell-cranks are equal 85 in length to the corresponding portions of the trip-levers, the rods 27 and radius-bars 19 are parallel and the trip-levers and bell-cranks are always parallel, as is well understood. Each corresponding bell-crank and trip-lever may 90 also be actuated independently of the others. The other arm of each bell-crank is intermediate pivoted to a corresponding feeler-rod 29, movable endwise in transverse parallel 95 guide-bars 30 31 on the main standards 18, 19 and constantly pressed upward by encircling spiral springs 32, resting on the guide-bar 30 and pressing against stops 33 on the feeler-rods. (See Figs. I and VIII.) The ends of 100 the feeler-rods are pointed and normally bear 100 against an endless pattern belt or chain 34, preferably of sheet metal, perforated at predetermined points with holes 35 for the entrance of the feeler-rod points. This pattern-belt is shown as carried by rollers 36 37 and 105 driven by friction-feed devices, hereinafter described, in such manner that when engaged by the feelers its further progress is arrested. As the pattern-belt moves, the feeler-rods are 110 forced by their springs into their appropriate 110 holes therein until stopped by their stops 33, thus carrying the bell-cranks with them and 115 forcing their connected trip-levers into position to engage with the warp-carriers. Fig. I shows the respective engaged and disengaged 115 relation of the parts. The organization is such that the trip-levers assume the engaging attitude when they are in their most advanced position, and consequently seize 120 their respective warp-carriers and carry them 120 to the opposite side of the median line of the warp, the unengaged carriers meanwhile retaining their normal position. As the warp-reels accompany the movements of their respective carriers, the shed is of course 125 changed. The bell-cranks and parallel rods retain the trip-levers and carriers positively in engagement as long as their feeler-rods engage the pattern-belt, and the number of warp-threads moved will correspond with the number of feeler-rods so engaged.

The pattern-chain, feeler-rods, bell-cranks, and parallel rods constitute what I term the "selecting" mechanism, while cam 24, link-

rod 21, and radius-bars 19 constitute what I term the "elevating" or "traversing" mechanism. The trip-levers 25 constitute parts of both the selecting and traversing mechanisms.

5 The weft is now inserted in the shed in a way hereinafter described, after which the retracted carriers are restored to their normal position by the reverse action of their trip-levers in the following manner: Cams 38 on 10 opposite ends of the driving-shaft retract properly-guided link-rods 39, connected with a transverse return-bar 43, through holes in which the feeler-rods 29 move freely endwise until their collars 44 abut against said bar, 15 when they are retracted out of engagement with the pattern-belt. This retraction of the feeler-rods correspondingly retracts the bell-crank and trip-levers, thereby disengaging the latter from the carriers. As this movement 20 disengages all the feeler-rods from the pattern-belt, the latter immediately resumes its travel, the cams 38 promptly advance the return-bar, and the feeler-rods resume their contact with the pattern-belt ready to return 25 to their appropriate holes therein. During this operation the trip-levers remain depressed ready to engage their appropriate carriers the moment their feeler-rods enter the holes in the pattern-belt. This saves time 30 which would otherwise be consumed in traversing the trip-levers.

The convergence of the warp-threads, hereinbefore mentioned, is effected as follows: A transverse comb 45 is secured on the main frame 0 under the warp-threads and slightly in the rear of the feed-rolls or weaving-line. This comb consists of a straight bar carrying a series of short upright teeth, preferably of small wire, as far apart as the warp-threads 35 are desired to be in the woven fabric, the threads passing singly between the teeth, which terminate a short distance above the warp-threads and hold them in correct position laterally. A similar comb 47, with its 40 teeth reversed, is secured on the opposite side of the warp to endwise-moving link-rods 48, pivoted at one end to the radius-bars 19, their opposite ends traversing suitable guides 49 on the frame. The comb necessarily moves 45 coincidently with the radius-bars, its teeth being at times brought very close to those of the fixed comb, with its teeth extending between and beyond the warp-threads. As the 50 engaged warp-reels and the reciprocating comb move coincidently, this comb receives the warp-threads withdrawn from the fixed comb and retains them in correct position until redelivered thereto, so that the warp-threads are alternately transferred from one 55 to the other, but are always retained in their proper places in the assembled warp. The warp-threads 10, Fig. III, which lie near the edges of the warp, are necessarily turned edge uppermost in passing the teeth of combs 45 60 and 47; but their position is rectified at the weaving-line by weaving in the weft, which causes them all to lie flat and right side up

after the weaving has once been properly begun. The combs 45 and 47 also serve by holding the warp-threads in proper lateral 70 position to prevent the fabric from being drawn together by the weft, thus dispensing with the use of a temple for this purpose. The weaving-arm or weft-carrier consists of a rigid longitudinally-perforated or tubular bar 50, 75 preferably of wood or other light material to facilitate rapid motion, with its rear or heel end mounted in a suitable traversing support and extending forward between the reel-carrier guides and combs to the weaving-line, being properly bent for this purpose. It is so organized as to traverse the shed from selvage to selvage in one direction only at each opening thereof. The free end or point of this weft-carrier terminates in a throat or 80 nose consisting of a metal tube 61, one end of which is secured on the weft-carrier, the other being broadened and flattened, as shown in Fig. VI, to adapt it to deliver a flattened weft-thread without turning. This continuous weft-thread 62 passes from a suitable reel longitudinally through the weaving-arm, issuing from its throat, and is delivered in its proper position in the fabric as the arm traverses the shed. The opposite end of the weaving-arm is rigidly mounted on the central arm or body of a T-shaped heel 52, the branches of which carry friction-rollers 53 54, traversing a transverse groove 55 in a plate 56 on the main frame. The central parts 100 of this groove are straight and substantially parallel with the weaving-line, while its ends are slightly curved in an arc of which the middle of the weaving-line forms the center, for a purpose hereinafter described. 105 A straight transverse slot or race 57 nearer to and parallel with the end of the frame is traversed by a slide-block 58, fitting therein and connected with the heel by a pivoted link-rod 59 at its center 60, Fig. II. A spur-pinion 65 on the driving-shaft 1 actuates a corresponding spur-gear 66 on a shaft 64, journaled in the main frame and carrying a cam 63, actuating a friction-roller 69 on a lever 67, oscillating on an intermediate pivot 110 115 on the bar 68. The other end of this lever is slotted to embrace a driving-pin 70 on the slide-block 58, the lateral movement of which correspondingly traverses the heel 52 in its groove and correspondingly moves the weaving-arm. Parallel transverse guide-plates 72 are secured on the frame, between which the end of the weaving-arm traverses to prevent its vertical displacement. While the heel 120 friction-rollers are traversing the straight central part of the groove (see Fig. III) the heel and point of the weaving-arm move simultaneously across the warp-threads parallel thereto as long as the throat traverses the shed. Then the rollers enter the curved part 130 of one end of the groove, (see Fig. II,) causing the heel to swing upon the throat as a center to the end of its course, the object of which operation is to enable the heel of the weav-

ing-arm to pass beyond the widely-separated warp-carriers, and at the same time to deliver from its throat only the necessary length of weft-thread. The weaving-arm traverses 5 the shed in one direction only at each opening of the warp, returning in the opposite direction at the next opening. To meet this requirement spur-gear 66 is made twice the diameter of pinion 65. Consequently driving-shaft 1 turns twice as fast as the cam 63. As heretofore remarked, the weaving-arm passes at each stroke between the guides 5 and 6 and the combs 45 and 47, as well as between the normally-situated warp-carriers 10 and those moved to open the shed. The reels and their supporting-levers are so organized that when in their normal position the upper parts of the reels lie below the corresponding parts of the guides, so that the weaving-arm 15 may traverse without interference. As the warp-carriers reach the opposite end of their traverse the free ends of the reel-levers 8 abut against the bar 73, thus causing the reel to swing around the pivots away from the weaving-arm to allow it to pass freely.

The feed of the warp is accomplished as follows, (see Fig. III:) The fabric passes between transverse rollers 80 81, one of which is fixed on a shaft 84, journaled in the main 20 standards 18, the left end of which shaft projects beyond the standard. The other feed-roller 81 is secured on a shaft 85, journaled in side blocks 86, moving in slots 87 in the main standards 18, and being forced toward the 25 fixed roll by spiral springs in a well-known way to compress the fabric. Spur-gears 88 89 on their respective roller-shafts 84 85 intermesh and drive the feed-rolls synchronously. Their surfaces may, if desired, be 30 fluted longitudinally to obtain a better bite and consequently more certain feed of the fabric as they revolve. A pinion 90 on the driving-shaft 1 drives a spur-wheel 91, turning loosely on the driving feed-roll shaft 84 35 and having plane sides. A friction-disk 92 is mounted on this shaft 84, being capable of moving freely endwise thereon, but is prevented from turning independently thereof by a spline on the shaft and a groove or key-way in the disk. A centrally-perforated 40 spring 94, preferably elliptic or dish-shaped, on this shaft is pressed against the friction-disk 92 by a nut 95, screwed on the shaft and correspondingly threaded. A collar 96, fast on 45 the shaft 84 on the opposite side of the gear-wheel 91, holds the gear-wheel and spring in contact, the pressure being regulated by the nut in a well-known way. The friction is sufficient to drive the feed-rollers, except 50 when prevented as hereinafter explained.

The woven fabric is wound on a cloth-beam 12, journaled in the main frame and actuated by a flexible endless band 115, encircling pulleys 113 114 on the main driving-shaft and 55 cloth-beam shaft 112, respectively, the band being loose enough to slip and let the cloth-beam rest when the feed-rollers stop.

The pattern-belt roller 36, hereinbefore mentioned, is mounted on a transverse shaft 100, journaled in the main standard 18, and 60 is furnished with a circular row of short radially-projecting pins 101, constituting in effect a sprocket-wheel engaging a corresponding row of holes in the pattern-belt to drive the latter positively. The other pattern-belt roller 37 is a plain cylinder mounted on a shaft 103, journaled in standards 104, 65 rocking on pivots on the main frame and adjustable by slots and set-screws 105 to accommodate belts of different lengths.

The pattern-belt roller 36, above mentioned, is driven positively from and synchronously with the feed-rollers by an endless chain 108, encircling sprocket-wheels 106 107 on feed-roll shaft 84 and pattern-belt-roller shaft 100.

From the foregoing description it will be seen that the revolving feed-rollers draw the fabric between them toward the cloth-beam on which it is wound until the feeler-rods engage and stop the pattern-belt, feed-rollers, the cloth, and cloth-beam, because the friction devices allow the driving mechanism of these parts to slip without interference with the working of the other parts of the loom. The length of the feed movement therefore 95 depends on the longitudinal distance between the holes in the pattern-belt, and may consequently be greatly varied. For instance, by this means the weft-thread may be arranged in the fabric in pairs, as in "open-cane" work, leaving 100 any space desired between said pairs; or it may be arranged in sets of three, four, &c.

It is well known that many different styles of weaving may be performed by the combination of a series of feeler-rods governing the 105 opening of corresponding warp-threads with a perforated pattern-belt. Many of these styles—such as twilled or figured work—may be combined in great variety in a fabric some portions of which are closely woven and other 110 portions "open" woven by the use of my improved opening and feeding devices above described.

Many of the features herein shown are described and claimed in another application 115 filed by me April 9, 1889, Serial No. 306,617; but nothing claimed in that application is claimed herein.

I particularly disclaim herein the combination of a weft-guide, mechanism traversing it 120 laterally relatively to the warp, warp-reels, and mechanism traversing them athwart the path of the weft-guide without interference therewith, and the combination, with the above elements, of warp-reel guides transversely divided in the path of the weft-guide, as these combinations constitute the subject-matter of the twentieth, twenty-first, and twenty-second claims of the above-mentioned application.

The operation of my improved loom will 130 readily be understood from the foregoing description.

Having thus fully described the construc-

tion, organization, and operation of my improved loom, what I claim therein as new and as of my own invention is—

1. The combination, substantially as hereinbefore set forth, of the warp-carrier having a transverse slot near its bottom for the passage of the warp-thread, the tension-pin movable endwise athwart said slot, its spring, and a screw to regulate the tension on the warp-thread.

2. The combination, substantially as hereinbefore set forth, of a warp-carrier, its tension-regulating device, a warp-reel, and a lever carrying the warp-reel and pivoted at an intermediate point on the carrier.

3. The combination, substantially as hereinbefore set forth, of a warp-carrier, its guides, a lever, its intermediate pivot on the carrier, and a warp-reel carried by the lever, whereby the reel is adapted both to traverse with and around the carrier.

4. The combination, substantially as hereinbefore set forth, of a warp-carrier, its guides, a lever, its intermediate pivot on the carrier, a warp-reel carried by the lever, and a stop against which the lever abuts to traverse the reel a greater distance than its carrier.

5. The combination, substantially as hereinbefore set forth, of a warp-carrier, guides separated by a space narrower than the length of the carrier, a lever, its intermediate pivot on the carrier, and a warp-reel carried by the lever, whereby the carrier and reel are controlled by one set of guides before being released from the other.

6. The combination, substantially as hereinbefore set forth, of a series of separate and independent warp-carriers, a warp-reel loosely mounted in each carrier, a trip-lever adapted to engage with each carrier, link-connections on which said levers rock, and a cam actuating the trip-levers through the link-connections to traverse the warp-reels athwart the line of the warp.

7. The combination, substantially as hereinbefore set forth, of a series of separate and independent warp-carriers, a warp-reel loosely mounted in each carrier, a corresponding series of trip-levers, link-connections and a cam actuating said levers athwart the line of the warp, a pattern-chain, feeler-rods, bell-crank controlled by the feeler-rods, and parallel bars connecting the bell-crank and trip-levers to determine which of the carriers shall be actuated to form the shed.

8. The combination, substantially as hereinbefore set forth, of a series of separate and independent warp-carriers, a corresponding series of trip-levers, a shaft on which they are intermediately pivoted, radius-bars carrying said shaft, a second shaft on or with which the radius-bars rock, a rotating cam, a connecting-rod actuated thereby pivoted to one of the radius-bars, bell-crank pivoted concentrically with the radius-bars, parallel bars connecting each bell-crank with its respective trip-lever, a perforated pattern-chain, and a

spring-pressed feeler-rod, one for each lever, engaging the pattern-chain at intervals determined by the perforations therein to determine the engagement of the respective trip-levers and carriers.

9. The combination, substantially as hereinbefore set forth, of the perforated pattern-belt, the spring-actuated feeler-rods, their collars, the return-bar, its connecting-rods, and cams simultaneously to release all engaged feeler-rods from the pattern-chain.

10. The combination, substantially as hereinbefore set forth, of the trip-levers, the shaft on which they are pivoted, bell-crank, parallel bars connecting them with the trip-levers, the perforated pattern-chain, spring-actuated feeler-rods engaging therewith, the stops or collars thereon, the return-bar and its connecting-rods, and cams whereby the trip-levers are engaged with and disengaged from the warp-carriers.

11. The combination, substantially as hereinbefore set forth, of a weaving-arm or weft-carrier, mechanism traversing it laterally relatively to the warp, guides on opposite sides of the path of the weft-carrier, warp-carriers movable on said guides athwart said path, means for actuating the warp-carriers, arms intermediately pivoted on the carriers, warp-reels carried by the arms, and stops causing the reels to swing around their pivots to clear the weaving-arm more effectually.

12. The combination, substantially as hereinbefore set forth, of a series of separate and independent warp-reels, the warp-reel carriers, trip-levers engaging therewith, radius-bars carrying said levers, a link-rod and cam for traversing the warp-reels athwart the weaving-line, a fixed comb on one side of the warp to separate the threads, a movable comb on its opposite side, and link-connections with the trip-lever-actuating mechanism to actuate said comb coincidently with the warp-carriers.

13. The combination, substantially as hereinbefore set forth, of the trip-levers, their radius-bars, the shaft with which they rock, their connecting-rod and cam, a link rod or bar pivoted to the radius-bar, guides for said rod, and a comb carried by the rod actuated in opening each shed.

14. The combination, substantially as hereinbefore set forth, of a series of separate and independent warp-reels, mechanism traversing them athwart the weaving-line, a fixed comb on one side of the warp, a movable comb on its opposite side, mechanism reciprocating said comb coincidently with the warp-reels, a weft-carrier, and mechanism traversing it athwart the warp between the combs.

15. The combination, substantially as hereinbefore set forth, of the weft-carrier, its intermediate heel, friction-rollers carried by the heel, a guide-plate having a transverse groove with curved ends, in which the rollers travel, a slide-block traversing in a transverse slot in the plate behind and parallel with the front

groove, a link pivoted at one end to the sliding block and at the other to the heel, a cam, and a slotted rocking lever actuated thereby to traverse the weft-carrier athwart the warp 5 and in its shed.

16. The combination, substantially as hereinbefore set forth, of the weft-carrier, its heel, friction-rollers carried thereby, the plate having a transverse groove therein with curved 10 ends, in which the rollers travel, a slide-block traversing in a transverse slot in the plate, a link connecting the slide-block and heel, and transverse guides in which the heel end of the weft-carrier travels to prevent vertical 15 displacement.

17. The combination, substantially as hereinbefore set forth, of feed-rolls, intermeshing gears thereon, a spur-wheel loosely mounted on the shaft of one of the feed-rolls, means 20 for driving the spur-wheel, friction-disks on opposite sides of said wheel, a perforated pattern-chain, its carrying-rolls, a sprocket-wheel and chain connection between the pattern-chain-roller shaft and the feed-roll carrying 25 the friction-disk, and spring-actuated feeler-rods engaging the pattern-chain to stop both it and the feed of the fabric.

18. The combination, substantially as hereinbefore set forth, of the perforated pattern-chain, its intersecting feeler-rods, its carrying-rolls, a sprocket-and-chain connection between the pattern-chain-roller shaft and the feed-roller shaft, the feed-rollers, their friction driving-gearing, the cloth-beam, and its yielding driving-belt driven from the same source as 30 the feed-rolls, whereby the feed-rolls and cloth-beam are simultaneously driven and stopped.

19. The combination, substantially as hereinbefore set forth, of the pattern-chain, its 40 driving-connections with the feed-rollers, the spring-actuated feeler-rods intersecting the pattern-chain to stop the feed, their releasing mechanism, the feed-rolls, the cloth-beam, and their frictional driving-connections, whereby 45 the weaving may proceed while the feed stops.

In testimony whereof I have hereunto subscribed my name.

HENRY B. MORRIS.
